FOREIGN PATENT DOCUMENTS

WO 9945835 A2 9/1999

Primary Examiner — David G Muller(74) *Attorney, Agent, or Firm* — Heslin Rothenberg Farley & Mesiti P.C.(57) **CLAIM**

The ornamental design for reinforcement arms and collar for a cannula tip, as shown and described.

DESCRIPTION

FIG. 1 is a perspective view of reinforcement arms and collar for a cannula tip comprising the new design;

FIG. 2 is a side view thereof;

FIG. 3 is a top view thereof; and,

FIG. 4 is a bottom view thereof.

The broken line showing is included for the purpose of illustrating portions of the article and forms no part of the claimed design.
